Earl M. Scanlan, ^{INVENTOR.}

John Scanlan
ATTORNEY.

UNITED STATES PATENT OFFICE.

EARL M. SCANLAN, OF DENVER, COLORADO.

AUTOMOBILE ORNAMENT.

Application filed August 7, 1923. Serial No. 656,211.

To all whom it may concern:

Be it known that I, EARL M. SCANLAN, a citizen of the United States, residing at Denver, in the county of Denver and State 5 of Colorado, have invented certain new and useful Improvements in Automobile Ornaments, of which the following is a specification.

This invention relates to ornaments for 10 automobiles and most particularly to ornaments designed to display the initials of the owner of a motor vehicle, in the form of a monogram, at the front of the radiator of the same.

15 It is an object of my invention to provide a monogram of the above described type, composed of two or more separate metal characters which are interwoven and rigidly fastened together at their points of inter- 20 section.

A further object of the invention is to provide a monogram thus constructed, with simple and convenient means for fastening it to the honeycomb web at the front of an 25 automobile radiator, and still another object of the invention is to produce a monogram of the above described character which is composed of metal characters of uniform proportions.

30 By the use of my invention, two or more letters of an alphabet may be quickly combined into a monogram of artistic and ornamental appearance, which is readily fastened at the front of an automobile by the 35 means provided for that purpose.

It is a salient feature of the invention that the letters combined into the monogram are fastened together without the use of frames, cross bars or other extraneous supports, and therefore, are similar in appearance to the costly monograms cut out of a 40 single metal plate, at present in use.

The letters employed in producing the monograms of my invention, are separately 45 cut or stamped from sheets of metal of sufficient pliability to permit of the letters being interwoven into any desired combination and they may be nickel-plated, silvered, oxidized or otherwise finished to enhance 50 their ornamental appearance.

An embodiment of my invention has been illustrated in the accompanying drawings in the several views of which like parts are similarly designated and in which—

55 Figure 1 represents a face view of a mono-

gram made of the letters G, M and R, in accordance with my invention;

Figure 2, a reverse view of the same, and Figure 3, a section taken on the line 3—3, Figure 1.

Referring more specifically to the drawings, the three characters G, M and R which as stated before, are made separately of pliable sheet metal, have been designated by the reference numeral 5.

The letters are interwoven by bending parts of one over the edges of intersecting parts of another and they are rigidly fastened together at their points of intersection by patches of solder 6. This method of connecting the letters is preferred by reason of its simplicity, ease of application and cheapness, but I desire it understood that other fastening means such as rivets or the like, may be used within the spirit and scope of the invention.

The means for fastening the monogram to an automobile, consist in the construction shown in the drawings, of slender wires 7 of pliable metal one end of which is fastened at the back of the monogram by patches of solder 8.

To fasten the monogram to the radiator, the wires are inserted through meshes of the honeycomb web thereof and they are bent upon the rear surface of the web after the monogram has been drawn against the front of the same.

It will be apparent that while the ornaments constructed in accordance with my invention are particularly designed to be secured at the front of an automobile radiator, they may also be used on the doors or other parts of the vehicle by providing means adapted to fasten them upon an im- 95 perforate surface.

By making the characters of which the monograms are formed, of uniform proportions, two or three alphabets made by the same set of dies, are all that is required to 100 construct monograms of any two or three initials.

The letters are interwoven and fastened together in the manner hereinbefore described, in a few minutes and the ornaments 105 may thus be produced at a very low cost.

Having thus described my invention, what I claim and desire to secure by Letters Patent is:

1. An automobile ornament of the char- 110

acter described, comprising a monogram composed of a plurality of terminally free interwoven characters made separately of pliable metal and fastened together at their 5 points of intersection.

2. An automobile ornament of the character described, comprising a monogram composed of a plurality of terminally free interwoven characters made separately of 10 pliable metal and soldered together at their points of intersection.

3. An automobile ornament of the character described, comprising a monogram composed of a plurality of terminally free 15 interwoven characters made separately of pliable metal and fastened together at their points of intersection, and means for securing the ornament to an automobile or the like, fastened to the monogram.

20 4. An automobile ornament of the character described, comprising a monogram composed of a plurality of terminally free interwoven characters made separately of

pliable metal and fastened together at their 25 points of intersection, and means for securing the ornament to an automobile or the like, fastened at the back of the monogram.

5. An automobile ornament of the character described, comprising a monogram composed of a plurality of terminally free 30 interwoven characters made separately of pliable metal and fastened together at their points of intersection, and means for securing the ornament to an automobile or the like, fastened by solder at the back of the monogram.

6. An automobile ornament of the character described, comprising a monogram composed of a plurality of interwoven characters made separately of pliable metal 40 and fastened together at their points of intersection, and wires of pliable metal fastened at the back of the monogram.

In testimony whereof I have affixed my signature:

EARL M. SCANLAN.
